(57) **CLAIM**

The ornamental design for a shoe, as shown and described.

DESCRIPTION

FIG. 1 is a perspective view of a shoe according to a first embodiment of the design;

FIG. 2 is a front view of a shoe of the embodiment of FIG. 1;

FIG. 3 is a back view of a shoe of the embodiment of FIG. 1;

FIG. 4 is a left view of a shoe of the embodiment of FIG. 1; FIG. 5 is a right view of a shoe of the embodiment of FIG. 1;

FIG. 6 is a top view of a shoe of the embodiment of FIG. 1; FIG. 7 is a bottom view of a shoe of the embodiment of FIG. 1;

FIG. 8 is a perspective view of a shoe according to a second embodiment of the design;

FIG. 9 is a front view of a shoe of the embodiment of FIG. 8;

FIG. 10 is a back view of a shoe of the embodiment of FIG. 8;

FIG. 11 is a left view of a shoe of the embodiment of FIG. 8;

FIG. 12 is a right view of a shoe of the embodiment of FIG. 8;

FIG. 13 is a top view of a shoe of the embodiment of FIG. 8; and,

FIG. 14 is a bottom view of a shoe of the embodiment of FIG. 8.

The broken lines are included for illustrating environmental aspects only and form no part of the claimed design. The dotted lines, which denote a line of stitching, similarly form no part of the claimed design.

1 Claim, 12 Drawing Sheets
